ABSTRACT: A single reference frequency source is coupled to a series of controlled period multipliers (frequency dividers) for selecting a musical keynote and for producing selected output tones that vary according to extensions of the natural or diatonic scale. The output tone selectors are arranged in a two-dimensional array correlating tonal intervals with spatial relationships.

**MUSICAL INSTRUMENT AND METHOD EMPLOYING
REFERENCE FREQUENCY SOURCE AND CONTROLLED
PERIOD MULTIPLIERS THEREFOR**

SUMMARY OF THE INVENTION

A series of controlled period multiplier circuits (frequency dividers) is coupled to a reference frequency source and each of the multiplier circuits multiplies an applied signal period by one of several selectable integers as selected by control signals applied thereto. This technique is used in an electronic musical instrument to generate selectable musical tones in accordance with both the diatonic musical scale and a music scale described previously by John Redfield (see: J. Redfield, "Music, A Science and an Art"; A. Knopf, Inc., N.Y., 1949). One embodiment of this invention provides a twelve interval per octave extension of both of these scales and also includes means for generating these scales transposed to any selectable keynote. Additional selectable binary period multipliers extend the tonal range over as many octaves as may be desired and a two-dimensional keyboard array facilitates manual playing of the instrument.

DESCRIPTION OF THE DRAWINGS

FIG. 1 is a simplified diagram of one embodiment of the musical instrument of the present invention;

FIGS. 2a and b are block diagrams of the controlled period multiplier used in the musical instrument of the present invention;

FIG. 3 is a block diagram of the preferred embodiment of the present invention; and

FIG. 4 is a pictorial diagram of the keyboard arrangement in the embodiment of FIG. 3.

DESCRIPTION OF THE PREFERRED EMBODIMENT

The relative frequencies of the tones of the diatonic scale are well known, and the minimum integers representing these frequencies over a little more than an octave range are shown in the following Table 1, column 1. The corresponding periods (i.e., the reciprocals of frequency) are proportional to the minimum integers which are shown in column 3 and which are obtained by dividing 4,320 by the corresponding integer shown in column 1. The integers of column 3 are factored into products of prime factors as shown in column 4. These factors can be regrouped in many different ways, and it has been discovered that the two groupings shown in columns 5 and 6 are particularly attractive because they provide the alternate factor products shown below columns 5 and 6. These simple

the musical tones and they also produce useful new musical scales.

Referring now to FIG. 1, there is shown the block diagram of one embodiment of the instrument according to the present invention for operation over an octave range of output frequencies or tones using controlled period multipliers 11-15 to provide the alternate factors derived in column 5 of Table 1. Thus, by selectively controlling these controlled period multipliers from control signal source 17 the frequency of the reference signal source 9, as later described herein, is divided down, and seven tonal intervals per octave may be generated at the output 19. The controlled period multipliers as referred to herein and as shown in FIG. 1 are combinations of digital logic elements as shown, for example, in FIG. 2a which receive a periodic input signal and produce a periodic output signal which has an output period that is equal to the period of the periodic input signal multiplied by an integer that is selected by control signals applied to the logic elements. The set of selectable integers chosen for this example is 9 or 8. Elements 8, 10, 12 and 14 are conventional J-K flip-flop circuits such as those commercially available in integrated circuit form designated as type SN7473. When the control signal applied to element 14 is in the low state, the Q output 18 of element 14 is low and the output of gate 22 is high and elements 8, 10 and 12 act as a three-stage binary counter with P_{out} equal to eight times P_{in} . On the other hand, if the control signal input is high, the output of gate 22 will go low in response to one of the eight counting states of elements 8, 10 and 12, thereby disabling the input to element 8 for one period of the input signal. On this extra input period, the Q output 18 of element 14 is driven low so that the input to element 8 is reactivated for the next input period. P_{out} therefore is equal to nine times P_{in} when the control signal is high.

FIG. 2b shows the symbol used herein to represent a controlled period multiplier with the selectable multiplying integers 9 or 8. The selectable multiplying integers can be changed to 5 or 4 by eliminating element 10 from FIG. 2a and connecting the $\bar{Q}$ output of element 8 to the clock input of element 12. It should therefore be apparent to persons of ordinary skill in the field that controlled period multipliers with other sets of selectable multiplying integers may readily be designed and constructed in accordance with the principles above. Also, it should be noted that other circuit arrangements for dividing an input frequency by a controllably selected factor may be used as the controlled period multipliers in the present invention (see, for example, "A Variable Counter Design Technique," E. L. Renschler, IEEE Trans. on Computers, July 1968, pages 694 et seq.).

The cascade connection, as shown in FIG. 1, of three controlled period multipliers 11, 13 and 15 of the type shown in FIG. 2 thus provide period multiplication in response to com-

H = Control input signal C is high

L = Control input signal C is low

It should be noted that this set includes all of the integers representing the relative periods of the tones Do through Ti in Table 1, and it should also be noted that the configuration of FIG. 1 provides one additional combination of factors, namely 8x4x4, not listed in Table 1. Introduction of this additional tone generated by this combination produces a scale that divides the octave into eight intervals. These intervals, expressed as ratios of successive frequencies from lowest to highest, are: 9/8, 10/9, 16/15, 135/128, 16/15, 10/9, 9/8, and 16/15. This set of eight intervals reduces to the seven-interval diatonic scale if the fourth and fifth intervals are combined (multiplied) and it also reduces to the seven-interval Redfield scale, in the Daleth mode, if the third and fourth intervals are combined. Combining of successive intervals is readily accomplished by not using the encompassed tone.

The factors shown in column 6 of Table 1 can be realized by changing the controlled period multiplier 13 of FIG. 1 to permit selection of the integers 5 or 6. This configuration also produces an eight-interval scale with successive frequency ratios of: 10/9, 81/80, 10/9, 16/15, 9/8, 10/9, 9/8 and 16/15. The diatonic scale is thus produced if the first and second intervals are combined, and the Redfield scale in the Aleph mode is produced if the second and third intervals are combined.

The principles demonstrated thus far are incorporated into the preferred embodiment of the present musical instrument shown in block diagram form in FIG. 3. The scale generator section, as in FIG. 1, consists of controlled period multipliers 31, 33, 35 and 37 that are controlled by the tone selector 30. Multiplier 37 provides one of three multiplying factors which extends the range of this part of the instrument to an octave and a half. Also, multiplier 35 is added to give a scale having 12 intervals per octave. Table 3 below lists the relative periods of the tones of this scale along with one possible assignment of tone names with corresponding frequency ratios and interval names as described in the literature (see, for example, "The International Cyclopedia of Music and Musicians," Oscar Thompson editor, 9th Ed.; Dodd, Mead and Co., N.Y. 1964, page 12).

Table 3

Relative Period	Tone Name	Frequency Ratio to Do	Interval from Do

400	Tu	9:5	Minor 7 th
384	Ti	15:8	Major 7 th
360	Do'	2:1	Octave

Unlike the equally tempered 12-tone scale, this scale does not provide for transposing the same scale into different keys, but it does provide a much wider variety of modes. The ability to transpose this scale into different keys is provided by the scale transposer section which consists of multipliers 41, 43 and 45 which are similar to those shown in FIG. 1 and which are controlled by the keynote selector 40. The scale transposer section can be visualized as a means for providing a set of selectable reference signals for the scale generator section where these reference signals in turn form a musical scale as determined by the scale transposer section.

Oscillator 47 provides the periodic signal which is multiplied by the various factors to produce the output tones. An oscillator frequency of 68.4288 MHz. in the instrument of FIG. 3 produces output tones into the third octaves above and below middle C. It is practical to build oscillators and period multipliers operating at 68 M MHz., but it may be economically advantageous to reduce this frequency by eliminating one or more period multipliers such as 41 and selecting equivalent frequencies by using some selectable frequency determining elements in the oscillator circuit 47.

The octave extender section is a series of conventional flip-flop circuits 51, 53, 55 with a gated bypass under the control of range selector 50 which provides for shifting the output of the scale generator in octave steps. The output waveforming circuits consist of a flip-flop circuit 57 for producing a square wave followed by an amplifier 20 which also responds to control unit 58 to gate the signal on and off and to selectively control and amplitude modulate the signal. Control element 48 provides for altering the reference frequency about its nominal value to produce small variations in pitch and to introduce vibrato in the audio signal produced at output 19.

It should be apparent that the controlled period multipliers can be rearranged in any order without altering the output signal and that some of the elementary multipliers could be combined. For example, multipliers 33 and 35 could be combined into a single multiplier with selectable multiplying integers of 16, 20 or 25. In addition, several similar channels of multiplier units 31-37 may be connected to receive reference frequencies, say, from the scale transposer section for producing additional tonal frequencies which can be combined in amplifier 20 to produce more than one tone simultaneously.

In the present embodiment of this invention the control console includes a keyboard for the tone selector 30 consisting of a set of switches arranged in a two-dimensional array, as shown in FIG. 4. The selectors for the tonal frequencies are arranged in rows and columns which need not be orthogonal although they are drawn so for simplicity. The rows are shown horizontally with six selectors per row and with two rows per octave. Within a row the successive selectors, moving from left to right, increase the selected tonal frequency by a Major 2nd alternating with a Minor tone. The columns are shown vertically, and within a column successive selectors, moving from bottom to top, increase the selected tonal frequency by either a Perfect 4th or a Doric 4th (a frequency ratio of 27: 20). Any number of octaves could be included by extending the array of selectors in accordance with the pattern established in FIG. 4.

The "selector vector" from any first selector to any second selector is defined as the vector drawn from the center of the first selector position to the center of the second selector position. Two selector vectors are equal if they have equal lengths and directions, and this equality is independent of positional translation about the pattern of selectors shown in FIG. 4.

FIG. 4 also shows the relative periods of the selectable tones, and the "tonal interval" from any first tone to any second tone is defined as the ratio of the period of the first tone divided by the period of the second tone.

An important property of this set of tonal frequencies combined with this array of selectors is that all pairs of tones having equal tonal intervals also have equal selector vectors. Therefore, if the scale and range of the keyboard permit a melodic pattern or a chord to be translated in pitch then the corresponding fingering pattern will be simply translated in

position. This consistent relationship between tonal patterns and geometrical selector patterns, together with the independent operation of keynote selector 40, makes it relatively easy to create and play music on the instrument of the present invention.

A musical instrument constructed in accordance with the present invention is thus ideally suited for playing music in the various modes of the diatonic scale and for developing the musical potential of the extensions of this scale which have been presented herein. The pitch of every tone in every musical key is as accurate as the frequency of the reference oscillator, and an ideal accompaniment for vocal music is provided by these precise tones extending the natural scale of Ptolemy.

I claim:

1. Signal-period multiplying apparatus for a musical instrument comprising:

first circuit means including logic elements which are responsive to first logic control signals applied thereto and being adapted to receive a periodic input signal for producing a periodic output signal having a period equal to the period of the input signal multiplied by an integer which is selectable in response to said first logic control signals from a first set of at least two different integers which are greater than unity and which have no common factors; and

at least second circuit means including logic elements which are responsive to second logic control signals applied thereto and being adapted to receive the periodic output signal from said first circuit means for producing a periodic resultant signal having a period equal to the period of said periodic output signal multiplied by an integer which is selectable in response to said second logic control signals from a second set of at least two different integers that are greater than unity and which are different from said first set and which have no common factors.

2. Signal-period multiplying apparatus as in claim 1 wherein:

one of the first and second sets of integers includes as said one integer the integer nine and the other of said first and second sets of integers includes as said one integer the integer five; and

another integer in each of said first and second sets is different from the respective said one integers by the value one.

3. Signal-period multiplying apparatus as in claim 1 for producing a plurality of periodic resultant signals of different periods according to a musical scale comprising:

controlled signalling means for applying said first and second logic control signals to the logic elements in said first and second circuit means for multiplying the period of a periodic input signal applied to the first circuit means by a plurality of factors in accordance with a progression of a musical scale.

4. Signal-period multiplying apparatus as in claim 1 which produces discrete signal frequencies according to a musical scale, the apparatus comprising:

signal means responsive to logic control signals applied thereto and coupled to the successively connected first and second circuit means for producing therewith discrete signal frequencies in response to combinations of logic control signals applied to said first and second circuit means and said signal means including the progression from a first tone of:

a second tone having a frequency equal to 9/8 the frequency of the first tone;

a third tone having a frequency equal to 10/9 the frequency of the second tone;

a fourth tone having a frequency equal to 16/15 the frequency of the third tone;

a fifth tone having a frequency equal to 135/128 the frequency of the fourth tone;

a sixth tone having a frequency equal to 16/15 the frequency of the fifth tone;

a seventh tone having a frequency equal to 10/9 the frequency of the sixth tone;

an eighth tone having a frequency equal to 9/8 the frequency of the seventh tone; and

a ninth tone having a frequency equal to 16/15 the frequency of the eighth tone.

5. Apparatus in a musical instrument for producing discrete tones in accordance with a musical scale comprising:

reference period signal-generating means providing a sequence of regularly recurring events having a reference period; and

tone generating means coupled to said reference period signal-generating means for selectively altering said reference period to produce a set of output tones including:

a first tone having a first period representative of the reference period;

a second tone having a period 9/10 times the first period;

a third tone having a period 8/9 times the first period;

a fourth tone having a period 4/5 times the first period;

a fifth tone having a period 9/8 times the first period;

a sixth tone having a period 16/15 times the first period;

a seventh tone having a period 3/5 times the first period;

and

an eighth tone having a period 8/15 times the first period.

6. Apparatus in a musical instrument for producing discrete tones in accordance with a musical scale comprising:

reference period signal generating means providing a sequence of regularly recurring events having a reference period; and

tone-generating means coupled to said reference period signal-generating means for selectively altering said reference period to produce a set of output tones including:

a first tone having a first period representative of the reference period;

a second tone having a period 8/9 times the first period;

a third tone having a period 4/5 times the first period;

a fourth tone having a period 9/8 times the first period;

a fifth tone having a period 32/45 times the first period;

a sixth tone having a period 16/15 times the first period;

a seventh tone having a period 3/5 times the first period;

and

an eighth tone having a period 8/15 times the first period.

7. Apparatus as in claim 6 for producing discrete tones in accordance with a musical scale wherein:

said tone generating means produces a set of output tones including:

a first intermediate tone having a period 15/16 times said first period;

a second intermediate tone having a period 5/6 times said first period;

a sixth intermediate tone having a period 5/8 times said first period; and

a seventh intermediate tone having a period 5/9 times said first period.

8. Apparatus in accordance with claim 6 providing a selectable keynote comprising:

keynote selection means coupled to said reference period signal-generating means for multiplying said reference period by a factor selectable from the set of multipliers of said first period.

9. Apparatus for a musical instrument comprising:

a source of periodic reference signal;

signal-period multiplying means coupled to said source for receiving said periodic reference signal and generating a set of at least seven periodic tonal signals per octave over a range exceeding one octave, said periodic tonal signals having periods equal to the period of the reference signal multiplied by selectable ones of a set of integers corresponding to the relative periods of the tones of a musical scale, said integers being selectable in response to control signals applied thereto for designating the tonal signals selected from said set of periodic tonal signals; and control signal-generating means including a corresponding

set of selector means for each discrete tone, said selector means being disposed in a spatial array which extends by rows in one direction and by columns in another direction in skew relationship to said one direction to provide all equal tonal intervals with corresponding equal selector vectors. 5

10. A musical instrument comprising:
 a source of periodic reference signal;
 controllable period-multiplying means having an input and an output and being responsive to control signals for producing at the output thereof from a periodic signal applied to the input thereof a plurality of tonal signals which vary over an octave range in tonal intervals according to a musical scale; and
 a plurality of binary period multipliers, each having input and output and each being responsive to a control signal applied thereto for selectively translating a periodic signal applied to the input thereof by an octave; 15
 means coupling said controllable period-multiplying means and said plurality of binary period multipliers in selected order in cascade arrangement to receive the periodic reference signal from said source at the input of the cascade arrangement; and
 output means coupled to said cascade arrangement for acoustically radiating the translated tonal signals at the 25 output of the cascade arrangement.
11. Apparatus as in claim 10 comprising:
 musical key-transposing means responsive to key determination signals applied thereto for multiplying the period of a periodic signal received thereby by selected 30 factors corresponding to said tonal intervals in response to key determination signals applied thereto; and
 means coupling said key-transposing means in selected order within the cascade arrangement of said controllable period multipliers and said binary period multipliers 35

between said source and said output means.

12. Apparatus as in claim 10 comprising:
 musical key-transposing means coupled to said source of periodic reference signal and responsive to key determination signals applied thereto for selectively altering the period of said periodic reference signal to provide said tonal intervals.
13. The method of playing music according to a musical scale comprising the steps, performed in selected order, of:
 producing a first tone having a keynote reference frequency;
 producing a first intermediate tone having a frequency equal to 16/15 times the reference frequency;
 producing a second tone having a frequency equal to 9/8 times the reference frequency;
 producing a second intermediate tone having a frequency equal to 6/5 times the reference frequency;
 producing a third tone having a frequency equal to 5/4 times the reference frequency;
 producing a fourth tone having a frequency equal to 4/3 times the reference frequency;
 producing a fourth intermediate tone having a frequency equal to 45/32 times the reference frequency;
 producing a fifth tone having a frequency equal to 3/2 times the reference frequency;
 producing a fifth intermediate tone having a frequency equal to 8/5 times the reference frequency;
 producing a sixth tone having a frequency equal to 5/3 times the reference frequency;
 producing a sixth intermediate tone having a frequency equal to 9/5 times the reference frequency; and
 producing a seventh tone having a frequency equal to 15/8 times the reference frequency.
